SHIPPING CONTAINER

Welrose L. Newhall, Coraopolis, Ernest Willison, Greentree, and Joseph Stevens, Sewickley, Pa., assignors to Dravo Corporation, Pittsburgh, Pa., a corporation of Pennsylvania

Application September 3, 1948, Serial No. 47,666

9 Claims. (Cl. 220—1.5)

1

This invention is for shipping containers and relates to shipping containers for use in making rail, water, or other transportation of merchandise which is particularly likely to be pilfered when shipped without adequate protection.

In the shipping of many products, as for example toys, cigarettes, costume jewelry, cosmetics, and innumerable other products, especially in what are termed "L. C. L." or, less than carload lots, considerable loss is suffered by pilfering or by breakage of cartons or containers. This is especially true in marine shipments where the merchandise may be stored on a wharf. Also, damage is likely to be suffered by reason of exposure.

It has heretofore been proposed to provide shipping containers for less than carload lot shipments, but such containers as have been provided have been expensive and unsatisfactory in various respects. Wooden boxes have also been used, but this is expensive.

According to the present invention, there is provided a metallic shipping container of a size which can be accommodated to use on trucks, rail cars, and steamships, and even river barges. It is so constructed that it may be handled by means of fork lifting trucks or by means of an overhead crane, as well as by platform trucks or by other methods. The boxes are so constructed as to resist rough handling and heavy impact. They are also constructed so that they may be placed close to one another, and one may be placed upon another with a minimum loss of head room. This is important, especially insofar as storing in the holds of ships is concerned, or temporary storage on wharves or in warehouses. The container, while being strong, is relatively light. In addition to providing these features, it is weather-tight, in that rain, even though it be blown by wind, or snow, will be effectively excluded. At the same time adequate ventilation is provided to prevent excessive condensation inside the box, particularly when a change of temperature occurs. Additionally the containers are so constructed that partitions may be temporarily arranged within them whereby fractional box-sized shipments, intended for the same general destination, can be accommodated.

These and other objects and advantages are obtained by our invention, which is more fully described in connection with the accompanying drawings, in which:

Fig. 1 is a perspective view of a shipping container constructed in accordance with our invention;

Fig. 2 is a side elevation thereof;

2

Fig. 3 is a front elevation of the shipping container;

Fig. 4 is a transverse longitudinal section with parts thereof broken away in the plane of line IV—IV of Fig. 3;

Fig. 5 is a partial transverse section through the container in the plane of line V—V of Fig. 2;

Fig. 6 is a horizontal fragmentary section in the plane of line VI—VI of Fig. 3;

Fig. 7 is a partial plan view of one edge of the container;

Fig. 8 is a horizontal section in the plane of line VIII—VIII of Fig. 2;

Fig. 9 is a bottom view of one longitudinal edge of the container;

Fig. 10 is a transverse section showing a temporary partition erected within the container;

Fig. 11 is a transverse section in the plane of line XI—XI of Fig. 10, showing the partition in place; and

Fig. 12 is a perspective view of a portion of the bottom of the container.

In the following description and claims, the front of the box will be the portion provided with doors, the back or rear wall will be the wall opposite the front, and the side walls will be the vertical walls between the front and back.

The box is formed with a bottom panel 5. It is constructed of a corrugated sheet 6 formed with square corrugations providing ridges 6a and channels 6b. These corrugations run crosswise of the box, that is, transverse to the axis running from the front to the back. Spot welded to the bottom plate 6 is a cover sheet 7 which is smooth, providing the floor for the box. At its side edges the bottom sheet 7 is turned down, as shown at 1a in Fig. 4, to overlap the ends of the corrugation in the plate 6. The purpose of this will be hereinafter more fully pointed out.

At the front edge of the plate 7 is an inwardly turned channel section 8 (see Fig. 3) forming the abutment for the door, and it has its flanges spot welded to the plate 7 and to the edge of the plate 6. At the rear edge of the bottom panel is a similar channel section 9 that has its flanges welded to the rear edge of plate 7 and to the rear edge of the corrugated plate 6.

The bottom as thus formed is smooth on top and corrugated on the bottom. The corrugated plate and the cover or smooth plate are integrated by spot welding, so as to provide a very strong bottom, the corrugations forming in effect a succession of box girders to give strength and rigidity to the structure.

55 The bottom is reinforced in a fore and aft

direction, by the structure hereinafter described, and in the construction shown, is further reinforced by skids 10 which run in a fore and aft direction adjacent each side edge of the bottom, and which are welded or otherwise firmly secured to the bottom. The skids have a vertical web 10a and a runner or flange 10b and a top flange 10c. These runners provide skids for sliding the box, and supports for elevating its bottom above the floor so that the prongs of a lifting fork or truck may be projected under it. To facilitate this latter operation, the webs of the skid immediately below the top flange 10c are provided with elongated openings 11 (see Fig. 2) at each side of the mid plane of the box so that the two prongs of such a fork can be projected through these openings, the prongs straddling the partition 12 which separates the openings. Also to enable the prongs to engage the corrugated bottom squarely, inverted channel sections 13 are welded into the corrugations 6a as shown in Figs. 4 and 12, these being arranged in rows, one of which is best shown in Fig. 8, and which are spaced inwardly from the skids a distance such as to be reached by the ends of a lifting fork truck. There are two such rows of channels, one inwardly from each skid. The channel sections 13 which are flush with the bottom of the floor panel of the box, assure that no matter how the lifting forks are inserted under the box, the box will be squarely supported. In other words, if these sections were not provided, one prong might engage a channel, and one a rib, and the box would be tilted when it was lifted, which might result in the box turning over. With these sections, such condition is prevented, as any fork following along a channel in the bottom will come under one of these sections 13. These sections, being welded in place, also stiffen the bottom.

Welded to each corner of the floor or base panel is a corner support, the supports at the front being designated 14, and those at the back, 15. Each corner support is formed of heavy sheet or light plate metal and is generally of angular form. The front corner elements have wings 14a and 14b. (See Fig. 8.) The wing 14a in turn bends inwardly, and has an upright channel section 14c formed integrally therewith. The wing 14b has an inwardly turned flange and lip portion designated 14d.

The rear corner posts likewise have wings 15a and 15b, each with a similar inwardly turned flange and lip formation along the vertical edge thereof and designated 15c and 15d.

Each corner post has a flat base plate 16 welded into the lower end thereof. This forms a foot for the corner column that closes the bottom of the column.

Side panels 17 are welded against the flanged ledges 14d and 15d of the front and rear posts respectively. These side panels are made up of corrugated metal. Preferably the corrugations are of a square form having relatively narrow outwardly projecting ridges 17a and wider in-turned grooves 17b. The narrow ridges 17a give the necessary rigidity to the panels, but they are less easily deformed by a blow which might be struck against them than a wider ridge would be with the same impact. On the other hand, the wider grooves 17b are protected by ribs against any blow that might be likely to damage them. The ribs 17a and the side panels are in alignment with the ribs on the floor panels, and this is for the purpose hereinafter more fully described.

As best shown in Fig. 5, the side panels lap down past the base panel, and an angle member 17c is welded along the bottom face and under the bottom edge of the side panel 17. However the angle does not completely close the bottom of the ribs or grooves 17a. This arrangement is definitely of advantage because any rain that drives against the sides of the box can run down the grooves 17 and drain through the space 17d at the bottom of the panel. On the other hand, air can enter the bottom of the box through the partially open ends of the ridges 17a, such openings being indicated at 17e (see Fig. 8). Because of this ventilation the contents of the box will be kept from sweating, resulting from temperature changes or changes in relative humidity. At the same time, wind-driven rain cannot enter the box.

Welded to the rear corner posts is an end panel 18 which is identical with the side panels so far as construction is concerned, there being an angle 18c along the bottom of the panel, and the end panel laps down past the bottom panel in the same way to provide for circulation of air and effective draining of water.

At the top of the box, along the two longitudinal edges, are angular metal plates 19 which are welded to the tops of the corner posts, and which provide a ledge 19a along each side of the box on the exterior thereof. These angular members at the top have a downwardly turned flange 19b which laps down over the outside of the side panels. An angle 19c welded to the inside of the horizontal portion of each of these members 19 laps down over the inside of the side panel 17 as clearly shown in Fig. 4. This provides a weather-tight, or weather shielded connection along the top edge of each side panel. As also shown in Fig. 5, the top edge of each side panel 17 is spaced below the members 19 so that air can circulate under the flange 19b up through the grooves in the side and down into the ribs at the side, thus providing for the circulation of air at the top of the box to eliminate sweating, while providing a weather-tight closure.

A corrugated top panel similar to the side and floor panels, is welded into place between the two longitudinal top side members 19. This corrugated top sheet is designated 20. Over the top sheet 20 there is a flat sheet metal cover 21, whose edges lap over the vertical flanges of the members 19 to shed water. The ribs and grooves in the top member 20 are also in line with the corresponding ribs and grooves in the side panels 17. The purpose of this will be hereinafter more fully described.

As shown in Fig. 4, a flat metal plate 22 extends upwardly from the top of the rear panel 18 under the downwardly turned rear edge 21a of the cover sheet 21. The corrugated top panel 20 terminates against this sheet 22 and is welded thereto at 22a.

An inverted angle section of heavy metal, designated 23, is welded onto the ledge 19 on the outside of the box near each corner of the box. The angle section is set on its two edges with the corner pointing upwardly in the general form of an inverted V. Each of these members 23 has a notch 24 cut therein and a hole 25. By reason of this arrangement, hooks at the ends of hoisting chains can be quickly hooked into the top of the box for hoisting and lowering the box. The notch 24 accommodates the body of the hook, while the hole 25 allows the point of the hook to pass therethrough. This provides a simple

but strong means for attaching hoisting chains to the box.

Also the ledges provide a surface, as shown in Fig. 2, whereby the skid 10 of one box may be set on the ledge of another box for stacking the boxes, one on top of another, without danger of their sliding. The slope and spacing of the members 23 is such that when one box is set on another, the inclined surfaces of the angle sections 23 tend to guide the skids of the superimposed box into position. The members 23 also provide abutments to prevent one box from sliding endways on another when they are superimposed.

The superimposed box of course is kept from sliding sideways on the box on which it rests by reason of the fact that its skids 10 straddle the higher top portions of the under box when one box is rested on the ledge of another. The lifting members 23 are spaced back from the extreme ends of the ledges so that there is a flat space on the ledge of each corner of the box where a superimposed box that has corner lugs instead of skids can be set.

The front of the box is provided with a movable closure means, this preferably being in the form of two hinged doors designated generally as 26 and 27. Each of the doors is made with a corrugated panel 26a and 27a respectively formed similarly to the side and back walls. Along each bottom edge of the door there is an angle strip 28 which laps under the edge of the sheet metal panel, but which does not completely close it. Each door is hinged to one of the corner posts 14, the hinge being welded, as best shown in Fig. 8, to that part of the corner post 14e which extends inwardly and connects to the post 14c. The hinges as thus located are set inwardly from the front of the corners, so that they are protected from impact. At the top of the end box is a top door framing member 29 which has a portion 29a over which the cover sheet 21 laps. It has an inwardly set portion 29b with a horizontal bottom ledge 29c and an upturned flange 29d. At the top of each corrugated door panel there is a metal strip 30 (see Fig. 4) that extends up past the lip or flange 29d on the front frame member 29. This member 30 has its top edge turned inwardly and downwardly as indicated at 30a. Thus there is provided a kind of labyrinth seal at the top of the door whereby any water which drives in over the top of the door drops down into the trough-like formation formed along the bottom edge of the member 29, and it can drain to each side of the box. This provides a weather-tight seal and avoids any need for a sealing gasket or packing around the top edge of the door. Likewise, as shown in Fig. 6, the vertical edges of the door panel adjacent the hinges are provided with annular strips 31. These strips form a labyrinth seal with the parts 14c of the corner posts. Water which drives in along the vertical edges of the two doors where they are hinged thus enters the part 14c and cannot get into the box. As previously stated, the lower edge of each door panel laps down past the level of the floor, and water driven against the front of the door thus drains downwardly. The door is therefore tight against wind-driven rain, even though no gasket or packing is used.

The vertical free edge of the door 27 is provided with an angle plate 32 extending from the top to the bottom of the door, the angle plate 32 having a ledge 33 at the back plane of the door. The free vertical edge of the door 26 is likewise pro-

vided with a strip 35 which is welded thereto, and which extends the full height of the door, and which has a lip portion 36 that overlaps the angle member 32 when the two doors are closed to provide a seal. Any rain that is driven in under the lip 36 can run out the vertical passage-way 37 provided between the two confronting edges of the doors.

The strip 35 arranged in the manner indicated also provides a cover over a vertical channel 38 forming a part of the door whereby to provide a housing for a locking bolt mechanism of a more or less conventional type designated generally as 39. With this type of latching mechanism, there are two bolts, one which extends downwardly, and one which extends upwardly from an operating cam or eccentric 40. This bolt in turn is moved by means of a lever 41 at the outside of the door. The lever 41 is so positioned that it may be moved when it sets the bolts in locking position adjacent a hasp (not shown) to enable a padlock to be passed through the handle and the hasp to prevent unauthorized operation of the door. If the door 26 cannot be opened, it is of course impossible to open the door 27.

At the front of the box there may be a card-holding clip 42 in which a shipping tag or way-bill may be inserted.

The door 27 is provided with spring-operated bolts 43 of a conventional type to which access can be had only after the door 27 is opened.

The latching bolts cooperate with keepers which are secured to the lower edge of the member 29.

The purpose of putting the grooves in the corrugated roof and in the corrugated sides into registration or in the same plane, is to enable a temporary partition to be erected at one or more points crosswise of the box. This is shown in Figs. 10 and 11 where a temporary partition is made up of horizontal wooden strips or battens 45. There are other vertical strips or battens 46. The strips 45 and 46 are bolted together where they intersect. The ends of the horizontal members are entered into the grooves formed by the outwardly extending ribs in the side walls, and the upper ends of the vertical strips 46 are likewise entered into the internal grooves formed in the corrugated top plate. By reason of the cross bars being thus fitted into the grooves, the partition cannot be moved after it is set into place. If desired, plywood or other sheet 47 may be secured to these strips 45 and 46. With this arrangement it is possible to segregate small shipments intended for the same general destination, and it is impossible for one shipment to become confused with another in transit. The partitions can be readily removed and reset at various points along the side walls, as may be required.

The box as thus constructed provides a strong, sturdy, but economical shipping container especially useful for the handling of less than car-load shipments, and is particularly useful in circumstances where the cargo is subject to pilferage. Being of strong construction with corrugated panels, they can withstand abusive handling. While sturdy and rugged, the weight is not excessive relative to their capacity. By reason of the smooth interior floor construction, in conjunction with the corrugated sheet under the bottom, a strong but smooth bottom is provided to facilitate loading and unloading. The structure is well adapted for handling by means of a lifting fork as well as by a crane, and like-

wise it can be skidded about over a platform or deck. While weather-tight, it is incapable of itself retaining water, and air circulation is provided to prevent sweating. By reason of the fact that containers may be stacked one upon another, and be interlocked when so stacked, they are safe to use on wharves, in holds of ships, and other places where conservation of floor space requires that they be placed one upon another.

The structure has further utility by reason of the arrangement herein described, permitting use of one or more transverse partitions at various places along the length of the box.

While we have shown and described one preferred embodiment of our invention, it will be understood that this is by way of illustration, and that various modifications and changes are within the contemplation of our invention.

We claim:

1. A shipping container of the class described having top, bottom, side and end walls wherein the bottom is comprised of a corrugated sheet metal panel substantially coextensive with the area of the container and having welded to the top surface thereof a flat sheet metal panel, said container having skids secured to the under side of the bottom along opposite edges thereof and extending crosswise of the corrugations and set inwardly from the plane of the side walls, and transverse fillers between downwardly-turned corrugations of the bottom flush with the bottom surfaces of the corrugations to prevent the fork of a lifting truck from entering a space between two corrugations, the skids being provided with spaced openings therethrough adjacent the plane of the bottom of the container through which the prongs of a lift truck may be entered.

2. A shipping container of the class described having a bottom panel coextensive with the area of the bottom of the container, said bottom panel being formed of a corrugated sheet to the top of which is welded a flat metal sheet, a corner post at each corner of the base panel of generally angular section, side and rear wall panels of corrugated metal welded to the corner posts and lapping past the edges of the base panel, angle-shaped top strips along each longitudinal edge of the top welded to the side panels and to the corner posts, said angle pieces having spaced depending flanges, one of which laps over the side panel, and one of which is inside the side panel, said angle-shaped top strips also having an upwardly-turned flange inside the plane of the side walls and a top panel secured to said angle pieces and comprised of a corrugated inner panel with a flat sheet metal panel welded thereto, the edges of the sheet metal panel overlapping said upwardly-turned flanges of said angle pieces.

3. A structure of the class described having a bottom panel, corrugated side panels extending upwardly at each side of the base, an angle member mounted on the top edge of each side panel, said angle members having a horizontal flange and a vertical flange set inwardly from the side walls of the box, whereby to provide a shoulder along the top of the box at each side thereof, and means providing a weather shielded connection between the horizontal flange of the angle and the corrugated side walls, the box having also end closures and having a top secured to the vertical flanges of the angle members and to the top edges of the end closures.

4. A shipping container having a bottom panel

formed of a corrugated sheet with a flat sheet coextensive with the area thereof welded thereto, said container having corrugated side walls and corrugated rear walls, said container also having corner posts at each corner of the base, the container having a top panel of less width than the bottom panel, and also formed of a corrugated sheet with a flat sheet welded to the top thereof, the container having angular metal sections along

10 each side of the top thereof extending from the front to the back corner posts on which said top panel is carried, the container having longitudinally extending skids thereon along the bottom edges thereof, the skids being so positioned that they may be set on the angle pieces of a similar container when two such containers are arranged in superimposed relation.

5. A container having a bottom panel, means for providing supports for holding the bottom 20 panel elevated above the floor on which the container is set, the container having corrugated side panels and having a corner post of angular section at each corner thereof, the container having a stepped top portion formed to provide a 25 horizontal ledge continuously along each side of the top for the resting of the supports of one container on the ledges of another container.

6. A container having a bottom panel, means for providing supports for holding the bottom 30 panel elevated above the floor on which the container is set, the container having corrugated side panels and having a corner post of angular section at each corner thereof, the container having a stepped top portion formed to provide a 35 horizontal ledge continuously along each side of the top for the resting of the supports of one container on the ledges of another container, and elements secured to the ledges near the ends thereof constituting stops for holding a superimposed container against endwise movement.

7. A container having a bottom panel, means for providing supports for holding the bottom 40 panel elevated above the floor on which the container is set, the container having corrugated side panels and having a corner post of angular section at each corner thereof, the container having a stepped top portion formed to provide a 45 horizontal ledge continuously along each side of the top for the resting of the supports of one container on the ledges of another container, said ledges being provided near each end thereof with an inverted V-shaped fitting welded thereto, which 50 fittings are provided with openings to accept the hooks of a hoisting chain.

8. A shipping container of the class described having a base and having corner posts at each corner of the base, said corner posts being of generally angular section, each corner post at the front of the section being formed with a substantially 60 channel-shaped flange extending vertically therealong, a cross member at the top of the container also of generally angular section, and having a portion which forms a substantially horizontally extending channel across the top of the front of the container, the top and sides of the door opening thus being defined by channels, these channels each having a web in the plane of the front of the container and each having an 65 outwardly-turned flange that forms the boundary of the opening and closure means across said front, said closure means having edge flanges thereon that extend into but are spaced from the aforesaid channels to form a labyrinth seal to exclude rain, said closure means having flat

surfaces in the plane of the closures which bear against said outwardly-turned flanges.

9. A shipping container of the class described having a composite base panel formed of a flat sheet of metal welded to the top of a corrugated sheet of metal with the corrugations extending in a crosswise direction of the container, a corner post of angle section at each corner of the base, a corrugated side panel at each side of the container welded to the corner posts at the front and back, the corrugated side panel lapping down past the edge of the base, an angular reinforcement along the bottom edge of each side panel with a horizontal flange that extends partway under the bottom edge of the side panel, allowing for the drainage of water and providing for the entrance of air into the container around the base, a similarly arranged end panel between the two corner posts at the rear of the container, angle pieces along each top edge of the container, extending from the front corner post to the back, and providing an offset in the top of the container, said angle pieces having inner and outer flanges between which the side panels are fitted and welded providing for ventilation at the top of the container, a roof panel of reinforced corrugated construction in the top of the container secured

5 to said angle pieces, and a metal plate on the back wall panel extending up and secured to the roof panel, a pair of doors constituting the front wall of the container, the corrugations in the side and rear panels having squared outwardly extending ribs of relatively narrow width between which are relatively wide channels.
